UNITED STATES PATENT OFFICE.

JOHN S. COLLISON AND WILLIAM A. WRIGHT, OF ORD, NEBRASKA.

WRENCH.

1,010,479.

Specification of Letters Patent.

Patented Dec. 5, 1911.

Application filed June 28, 1911. Serial No. 635,768.

To all whom it may concern:

Be it known that we, JOHN S. COLLISON and WILLIAM A. WRIGHT, citizens of the United States, residing at Ord, in the county of Valley, State of Nebraska, have invented a new and useful Wrench, of which the following is a specification.

This invention relates to wrenches, one of its objects being to provide a tool of this character which can be quickly adjusted and which can be used either for engaging nuts or for gripping and turning pipes and other round objects.

Another object is to provide a wrench which is cheap to manufacture, compact in construction, and will not readily get out of order.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings the preferred form of the invention has been shown.

In said drawings,—Figure 1 is a side elevation of the wrench. Fig. 2 is a longitudinal section therethrough. Fig. 3 is a perspective view of the movable jaw. Fig. 4 is a perspective view of the links and a portion of the adjusting screw used in connection with said jaw. Fig. 5 is a section on line A—B Fig. 1. Fig. 6 is a section on line C—D Fig. 1.

Referring to the figures by characters of reference 1 designates the head of the wrench, the same consisting of spaced side plates secured to or formed integral with a handle 2. This handle has webs 3 and 4 extending transversely thereof, there being openings between the webs and also between the web 4 and one end portion of the handle and between the web 3 and the head 1. Side strips 5 are formed on or secured to the handle 2 between the head 1 and the web 3 and these side strips have oppositely disposed slots 6 extending longitudinally therein, the side plates of the head 1 being formed with diagonally disposed slots 7.

A fixed jaw 8 is formed integral with the head 1 and cooperates with a movable jaw 9. This movable jaw has a shank 10 extending

through the head 1 and between the side strips 5, there being a diagonally disposed slot 11 in the shank and disposed substantially at right angles to the slot 7. A guide pin 12 extends through the slots 7 and 11 and is mounted to slide therein. The pin 12 also extends through openings 13 formed in links 14 which are movably mounted between the sides of the head 1 and between the strips 5. These links are formed with longitudinal slots 15 and are pivotally connected, at one end, to a head 16 formed at one end of an adjusting screw 17. Said screw is slidable within the webs 3 and 4 and that portion of the screw located between the webs is engaged by a nut 18. Said nut is held against longitudinal displacement by the webs as will be apparent by referring to Figs. 1 and 2. The inner end of the shank 10 has a guide screw or pin 19 extending transversely therethrough and is slidable within the slot 6, this pin or screw also extending rigidly through the slots 15.

It will be apparent that when the screw 17 is drawn toward the small end of handle 2 by rotating the nut 18, the links 14 will pull on the pin 12 and move it longitudinally of the slots 7 and 11, thus causing the jaw 9 to swing downwardly and to clamp upon the working face of the stationary jaw 8. By reversing the movement of the screw 17, the links 14 will be caused to push against the pin 12 and thus force it along the slots 7, thereby elevating the jaw 9, swinging movement of this jaw being permitted by reason of the fact that the pin 12 is extended through the slot 11 within the shank of the jaw. Slots 6 also permit any necessary play of the pivot pin or screw 19.

It will be apparent that this wrench can be quickly adjusted and by providing the operating mechanism described, the jaws can be caused to tightly grip upon any object to be operated by the tool.

Although the sides of the head 1 and the strips 5 have been shown integral with the head 1, it is to be understood that they can be made up of separate plates riveted or otherwise secured upon the sides of the handle.

What is claimed is:—

A wrench including a handle having a hollow head, a stationary jaw extending from the head, a movable jaw, a shank ex-

tending from the movable jaw and through the head, said shank and the sides of the head having diagonally disposed slots, the slots in the head being disposed at an angle 5 to the slot in the shank, a slidable and pivotal connection between one end of the shank and the handle, a connecting pin extending through the slots in the head and shank, links pivotally mounted on said pin, 10 said links being disposed within the handle, an adjusting screw pivotally connected to the links, and means mounted for rotation

within the handle and held against longitudinal movement thereby, for shifting the adjusting screw and the links.

15

In testimony that we claim the foregoing as our own, we have hereto affixed our signatures in the presence of two witnesses.

JOHN S. COLLISON.
WILLIAM A. WRIGHT.
